UNITED STATES PATENT OFFICE.

GEORGE GUENTHER, OF CHICAGO, ILLINOIS, ASSIGNOR TO HIMSELF AND
E. H. NEYMAN, OF NEW YORK, N. Y.

IMPROVEMENT IN THE MANUFACTURE OF GLUE.

Specification forming part of Letters Patent No. 97,771, dated December 11, 1869.

To all whom it may concern:

Be it known that I, GEORGE GUENTHER, of Chicago, in the county of Cook and State of Illinois, have invented certain new and useful Improvements in Glue; and I do hereby declare that the following is a full and exact description thereof.

Glue is ordinarily boiled down to the consistency of jelly, cooled in molds, and cut into thin slices by wires, which slices are subsequently dried on nets and stored and transported in the form of thin dried cakes, which require to be soaked, boiled, and stirred for a long period before the glue is ready for use. Besides the loss of time and labor involved in this operation, the adhesive quality of the glue is always liable to be seriously affected by partial decay in case of drying in the ordinary atmosphere, and by scorching and other causes when dried by artificial heat.

I take freshly-made glue of very good stock before the boiling has proceeded to the consistency required for molding and cutting in slices, and pour it into previously-heated cases, stop each tightly, and transfer it through suitable double doors or otherwise, in an inverted position, into a strong chamber, within which is maintained a temperature a little above 212° Fahrenheit and a pressure a little below the ordinary atmospheric. I can keep a sufficient vacuum by means of a moderate-sized air-pump. By supplying in one part of the same chamber a chemical agent that has a great affinity for water I succeed in maintaining a very dry atmosphere in the chamber, and the pressure within each case forces out a small quantity through the joints around the stopper or closed mouth, and this glue, by drying as soon as it appears on the exterior, forms a perfectly-tight seal.

I find that bottles of strong glass in the ordinary rounded form, but with shorter necks, may be used with advantage, corked with common or very inferior corks. This makes a very convenient form for my package, and the bottles, being cheap, may be broken whenever it is required to obtain access to the con-

tents. Tin cans, similar to those used in putting up fruit, may be used, if preferred; but in either case it is not essential to use rubber, resin, or other sealing agent, because the glue, caused to exude and dry, as described, forms at the same time a tighter and more adhesive mode of closing than can be procured by any other means, and at far less expense. After a very brief interval in the drying, or what I call the "vacuum," chamber, the packages may be removed and slowly cooled.

My glue may be kept for any period in any climate and under any conditions. When it is desired for use, the vessel may be opened either by moistening the glue at the mouth and opening, so as to preserve the vessel, or by breaking or cutting, and the semi-fluid contents are ready to be heated and diluted with water to any required extent and used immediately. My invention is intended more particularly for manufacturers, who not only require the very best kind of glue, but who use considerable quantities. A package, when opened, should be emptied entirely.

I believe that success may be attained in the manufacture of my packages by drying their mouths in the ordinary pressure of the atmosphere; but this requires a more delicate adjustment of heat, so as to get a temperature a little above the boiling-point of thick glue, and not enough above to damage the product. I prefer the partial vacuum described. It is then easy to obtain the desired effect with a very moderate heat—say 215° Fahrenheit.

I claim—

As a new article of manufacture, the within-described canned glue, prepared substantially in the manner and so as to combine the advantages herein set forth.

In testimony whereof I have hereunto set my name in presence of two subscribing witnesses.

GEO. GUENTHER.
